(57) **CLAIM**

The ornamental design for a pocketknife tool, as shown and described.

DESCRIPTION

FIG. 1 is a front elevation view of a pocket knife showing my new design with the blade in the open position;
FIG. 2 is a front perspective view thereof, with the blade in the closed position;

FIG. 3 is a top plan view thereof;

FIG. 4 is a bottom plan view thereof;

FIG. 5 is left side elevation view thereof;

FIG. 6 is a right side elevation view thereof;

FIG. 7 is a front elevation view thereof; and,

FIG. 8 is a rear elevation view thereof.

The broken lines depict portions of the pocket knife in which the design is embodied that are not considered part of the claimed design.
